US00D903700S

(12) **United States Design Patent** (10) **Patent No.:** **US D903,700 S**
(45) **Date of Patent:** ** *Dec. 1, 2020

(54) **DISPLAY SCREEN OR PORTION THEREOF
WITH A GRAPHICAL USER INTERFACE**

(71) Applicant: **JPMorgan Chase Bank, N.A.**, New York, NY (US)

(72) Inventors: **Amanda Valladares**, Brooklyn, NY (US); **Amanda Smith**, Brooklyn, NY (US); **Melora Zaner**, New York, NY (US); **Matthew Gromada**, New York, NY (US); **Jay E. Parsons**, Columbus, OH (US); **Jonathan Beck**, New York, NY (US); **Erika Scott**, Brooklyn, NY (US); **Claudio Esposito**, New York, NY (US); **Indeevara H. De Silva**, Lewis Center, OH (US); **Melissa Feldscher**, New York, NY (US); **Geoffrey L. Goetz**, Hilliard, OH (US); **Michael Thornton**, Westerville, OH (US); **Kimberly Chan**, New York, NY (US)

(73) Assignee: **JPMORGAN CHASE BANK, N.A.**, New York, NY (US)

(*) Notice: This patent is subject to a terminal disclaimer.

(**) Term: **15 Years**

(21) Appl. No.: **29/670,410**

(22) Filed: **Nov. 15, 2018**

Related U.S. Application Data

(63) Continuation-in-part of application No. 29/613,546, filed on Aug. 10, 2017, now abandoned.

CLAIM

The ornamental design for a display screen or portion thereof with a graphical user interface, as shown and described.

DESCRIPTION

The FIGURE depicts a front view of a display screen or portion thereof with a graphical user interface showing our design.

The broken line showing a display screen with graphical user interface is included for the purpose of showing portions of the article which form no part of the claim.
